UNITED STATES PATENT OFFICE.

FREEMAN J. WINCHELL, OF LYNN, MASSACHUSETTS, ASSIGNOR TO SAID FREEMAN J. WINCHELL, OF NAHANT, MASSACHUSETTS, JOHN L. SHEVENELL, OF HAVERHILL, MASSACHUSETTS, AND HELMAR G. JOSEPHSON, OF LYNN, MASSACHUSETTS, TRUSTEES.

SHANK REENFORCE.

Application filed February 11, 1920. Serial No. 357,995.

To all whom it may concern:

Be it known that I, FREEMAN J. WINCHELL, a citizen of the United States, and resident of Lynn, county of Essex, Commonwealth of Massachusetts, have invented an Improvement in Shank Reenforces, of which the following description, in connection with the accompanying drawings, is a specification, like characters on the drawings representing like parts in each of the several views.

This invention relates to metallic reinforcing members for stiffening the intermediate or instep part of a shoe sole and commonly known in the art as "shank-stiffeners." More particularly the invention relates to a type of shank-stiffener composed of a formed strip or plate of metal equipped with prongs adapted to be pressed into the material of the sole to secure the same thereto. One principal object of the invention is to provide a shank stiffener that is relatively very strong though of relatively small dimension and of an outline and cross section such that a maximum degree of stiffness is attained and at the same time the metal is so formed that it does not cut into, or form ridges in, the leather or other material of the soles when it is pressed thereonto. A further object is to provide a shank-stiffener presenting a smooth end that will not project up into the sole in an objectionable manner. A still further object is to provide an improved shank-stiffener that is equipped with fastening means arranged in a novel manner and so that the end of the stiffener is not apt to be pried out by the flexing of the sole, either in the course of the manufacture of the shoe or in the use thereof. The foregoing and other objects and advantages of the invention will more fully appear from the following detailed description, and the distinctive features of novelty will be pointed out in the appended claims.

45 Referring to the drawings:

Fig. 1 is a plan view of a shoe sole having the shank stiffener of my invention applied thereto;

Fig. 2 is a side or edge view thereof;

50 Fig. 3 is a plan view of the stiffener member on an enlarged scale;

Fig. 4 is an edge or side view thereof; and,

Fig. 5 is a transverse section on line 5—5 of Fig. 4.

10 indicates the stiffener member of my invention which is shown applied to a shoe sole S to reinforce the shank or instep portion thereof. This shank-piece is curved longitudinally as usual to conform to the instep curve of the sole and as best 60 shown in Figs. 2 and 4. The major intermediate portion of the stiffener is also curved or arched transversely as indicated at 10^a intermediate the width thereof to increase the stiffening quality of the member as will be understood, this intermediate transverse arch being preferably relatively deep, as shown. This arching of the piece transversely would tend to make the edges thereof press and sink into the leather of 70 the sole so as to cut the same more or less and make ridges therein, but in accordance with my invention this defect is obviated by turning the sides of such arch outwardly and, as illustratively shown, producing 75 small reverse grooves 10^b adjacent the sides of the piece. This results in presenting a smooth rounded seating and facing portion of the shank-piece at each side thereof to be pressed against the sole affording a firm, 80 reliable seat and eliminating the likelihood of injury to the sole, it being understood in this connection that the shank-stiffener members are in practice pressed into assembled relation with the sole under considerable 85 pressure which results in a close application of the shank-stiffener to the sole and in the embedding and upsetting of the securing prongs therein. In accordance with my invention the shank-stiffener is formed at its 90 rear end with securing prongs 11, these being shown as turned-in at each corner from the end of the shank-piece. This insures that the very extremity of the shank-piece at the rear end thereof will be held down close and 95 secure to the sole. At the front end of the shank-piece I form securing prongs 12 struck-in from the sides of the piece a short distance from the end thereof. This leaves a neck portion 13 of reduced cross section 100 and therefore capable of flexing somewhat more readily opposite these prongs, and it is to be noted that the prongs themselves are struck from the head or extremity 14, i. e.

the stiffener-piece is secured at the end by these prongs beyond, and through, the neck portion 13. This results in permitting the extremity or end head portion 14 of the 5 stiffener to be closely secured to the sole by the prongs 12 and in a manner so that it is not apt to be pried out on the flexing of the sole since this flexing will be taken up by the neck portion 13 which being some- 10 what reduced in cross section and not arched is readily adaptable for this purpose. A further advantage of having the prongs 12 struck from the sides of the piece as shown is that it saves stock to a substantial degree. 15 I am aware that the invention may be embodied in other specific forms without departing from the spirit or essential attributes thereof, and I therefore desire the present embodiment to be considered in all 20 respects as illustrative and not restrictive, reference being had to the appended claims rather than to the foregoing description to indicate the scope of the invention.

Having described my invention what I 25 claim as new and desire to secure by Letters Patent:

1. A shoe shank comprising a strip of struck up metal curved longitudinally and provided with a depression extending lengthwise there- 30 of, and terminating short of the ends, a rel-

atively narrow flange on each side of the depression and a pair of clinching teeth in each end portion of the shank.

2. A shoe shank comprising a relatively narrow strip of struck-up metal curved longitudinally and provided with a relatively deep intermediate transverse arch extending lengthwise thereof, but terminating short of one of the ends, a flat portion at an end of the arch having a pair of clinching teeth extending therefrom adapted to be driven into the leather, the sides of the said arch being relatively turned outwardly to provide a substantial area of contact with the leather backing. 40

3. A shoe shank comprising a narrow strip of metal, struck up into shape to give rigidity and a slight springy effect, a concave depression extending lengthwise thereof, but terminating short of the ends, the sides of the said depression flaring outwardly to provide flat, relatively narrow flanges, the thin edge of the metal being on the outer side of the flanges, flat portions at the ends of the depression and a pair of clinching teeth in 50 each end portion of the shank and in line with the said flanges.

In testimony whereof, I have signed my name to this specification.

FREEMAN J. WINCHELL.
